UNITED STATES PATENT OFFICE.

CHARLES H. MILLER, OF BROOKLYN, OHIO.

KITCHEN-RANGE.

No. 915,986.

Specification of Letters Patent. Patented March 28, 1909.

Application filed June 10, 1907. Serial No. 378,059.

To all whom it may concern:

Be it known that I, CHARLES H. MILLER, a citizen of the United States, residing at Brooklyn, in the county of Cuyahoga and State of Ohio, have invented certain new and useful Improvements in Kitchen-Ranges, and do declare that the following is a full, clear, and exact description of the invention, which will enable others skilled in the art to 10 which it appertains to make and use the same.

My invention relates to improvements in kitchen ranges which are provided with fire pots as usual adapted to use solid fuel, such 15 as wood and coal, a gas or vapor burner located beneath the oven separate from said fire pot, whereby either solid or liquid fuel can be used as may be found convenient, all substantially as shown and described and 20 particularly pointed out in the claims.

In the accompanying drawings, Figure 1 is a perspective view of a kitchen or cooking range embodying my invention and in which the front portion has been broken away to 25 disclose the location of the fluid burner. Fig. 2 is a front elevation of the range with the front plate thereof removed and the burner broken off at the front, and Fig. 3 is a vertical cross section of the range substantially on line 3—3, Fig. 2. Fig. 4 is a perspective view of the damper for the bottom draft space of the range and the crank and link connections between the same.

The range as herein shown is of somewhat 35 special and exclusive construction independently of said burner in that it has a bottom air or draft space, indicated by 2, through which fresh air is drawn and heated as it passes through the same from without into 40 the ash pit and thence up into the fire pot. Walls or plates 3 and 4 constitute the upper and lower sides of this draft space and wall or plate 5 represents the bottom of the oven. Ordinarily, for hard fuel alone, plate 3 is ex- 45 tended up against the inner wall of the ash pit, but in the present construction said plate is provided with a drop *a* to form a gas burner chamber next to said ash pit and which has air openings *a'* from space 2 into 50 said gas chamber. A heating space 6 for the oven extends from said burner about the rear of the oven to the top thereof, as usual, and draft flue F extends from bottom to top of the range at its rear as usual and has damper 55 controlled openings into the same both below and above the oven, as usual and as will now

be seen. If coal or wood be burned and the fire is well started the draft will be from over the top of the range down at the rear of the oven and beneath the same to exit or exhaust 60 opening controlled by damper 8. But if gas burner B be used the line of draft will be just the reverse of this and the exit for the products of combustion upward through the opening at the top of the range controlled by damper 10. 65 In the first case the products of combustion pass downward, and in the latter upward, but for starting the coal or wood fire upper damper 10 is usually opened to get a direct draft and quick fire. Damper 10 is prefer- 70 ably under separate hand control, as usual. In addition to these draft dampers there is also a special burner damper or plate 12, hinged above or over gas burner B and adapted to swing down and close the cham- 75 ber or space within which said burner is located and thus reestablish draft conditions for use of hard fuel in the fire pot. But when gas is to be used and not the hard fuel said plate is raised so as to open the burner to 80 the heating space beneath the oven whence the heat and products of combustion flow rearward beneath the oven and find exit through top damper 10. When thus raised plate 12 also serves to protect the bottom of 85 the oven immediately over the burner from excessive heat at that point and from burning out.

Lower draft damper 8 is directly associated with gas burner plate 12, because when said plate is raised and the burner is used damper 8 must necessarily be closed. Hence I have shown said parts 8 and 12 as mechanically and operatively associated one with the other in such manner that when plate 12 is 90 raised, as in Figs. 2 and 3, damper 8 will be automatically closed, and when said plate is lowered over burner B said damper will be opened. Of course these parts could be disassociated and operated separately, but this 95 is not the preferred way. Hence I provide plate 12 with a hinge wire or rod 14 which supports said plate over chamber *a* and burner B and which wire or rod extends beyond the ends of said plate relatively as 100 shown, and each extremity of which is bent at right angles as indicated at 15 and 16 respectively. End or extremity 15 comes to the outside of the range at the front and forms a handle or arm to control the throw of plate 12 to open or closed position, and a pivoted pawl or stop 17 is shown to engage 105 110

said extremity 15 and hold the said plate 12 open. At its opposite end arm 16 is connected by link 18 with a right angled arm 19 on damper 8, and said link has free connections at both ends so that the rotation of plate 12 on its hinge from closed position, Fig. 1, to open position, Fig. 2, will give damper 8 a quarter turn and close the same. Then as said plate 12 is closed the damper 8 is opened, and both parts are simultaneously operated through lever or arm 15.

Any suitable form of fluid burner B may be used, and with which it is practicable to burn both solid and fluid fuel at the same time. I do not plan to do this, but rather provide a range with convenient alterations as to the fuel, depending on local conditions. Obviously, if the gas should for any reason fail, as often occurs in cities using natural gas, solid fuel can at once be substituted and no great inconvenience be incurred.

What I claim is:—

1. A kitchen range having an oven with a heating space about the same and a draft flue at its rear with top and bottom outlets, a fluid burner pivoted beneath the front of the oven, a plate adapted to open and close over said burner and a damper for said bottom outlet operatively connected with said plate.

2. A kitchen range having an oven with a

heating space about the same and a draft flue open to said space both above and below the oven, in combination with a fluid burner next beneath the bottom of the oven at its front, a hinged cover adapted to open and close over the burner and a flue damper operatively connected with said plate. 35

3. A kitchen range having an oven with a heating space about the same, in combination with a fluid burner beneath the oven and a hinged plate over said burner adapted to protect the bottom of the oven from the direct heat of the burner and to open said heating space to the burner. 40

4. A kitchen range having a fire pot and an oven with a heating space about the same, and upper and lower outlets from said space, in combination with a fluid burner in said space, a plate hinged to open and close said space in respect to the burner, a damper for the lower of said outlets having linked connection with said plate and a damper to control the upper of said outlets. 45

In testimony whereof I sign this specification in the presence of two witnesses.

CHARLES H. MILLER.
